CLAIM

The ornamental design for a grip for soldering iron as shown and described.

DESCRIPTION

FIG. 1 is a perspective view of a grip for soldering iron showing our new design;

FIG. 2 is a front view thereof; the opposite side being a mirror image of the side shown herein;

FIG. 3 is a left side view thereof;

FIG. 4 is a right side view thereof;

FIG. 5 is a top view thereof; the opposite side being an identical image of the side shown herein;

FIG. 6 is a cross-sectional view taken along line 6-6 in FIG. 3 thereof, in which the internal mechanism is omitted;

FIG. 7 is an enlarged left side view thereof; and,

FIG. 8 is an enlarged right side view thereof.

The dash-dash lines depict portions of the grip for a soldering iron in which the design is embodied that are not considered part of the claimed design.
